(57) **CLAIM**

The ornamental design for a line replaceable unit active cable, as shown and described.

DESCRIPTION

FIG. 1 is a perspective view of a first embodiment of a line replaceable unit active cable of our new design; FIG. 2 is a bottom view thereof; FIG. 3 is a top view thereof; FIG. 4 is a front view thereof, a rear view being a mirror image; FIG. 5 is a left side view thereof, shown in enlarged scale; FIG. 6 is a right side view thereof, shown in enlarged scale; FIG. 7 is a perspective view of a second embodiment of a line replaceable unit active cable; FIG. 8 is a bottom view thereof; FIG. 9 is a top view thereof; FIG. 10 is a front view thereof, a rear view being a mirror image; FIG. 11 is a left side view thereof, shown in enlarged scale; and, FIG. 12 is a right side view thereof, shown in enlarged scale. The dashed broken lines in the drawings are for the purpose of illustrating environmental subject matter that forms no part of the claimed design.

1 Claim, 6 Drawing Sheets
